PRINTING MACHINE

Anton Stobb, Union Township, Hunterdon County, N. J., assignor to R. Hoe & Co., Inc., New York, N. Y., a corporation of New York

Application February 23, 1946, Serial No. 649,571

9 Claims. (Cl. 242—58)

1

This invention relates to a web supplying mechanism, and more particularly to a reel for supporting and successively moving a pair of web rolls to a feeding position, and which includes mechanism whereby a web can be fed under proper tension control to a printing machine.

Web roll supplying mechanisms are commonly used, with newspaper and other high speed printing machines, to shift the feed of the web from an expiring roll to a replacement roll without stopping or slowing down the printing machine. Web supplying mechanisms usually support a plurality of web rolls and move them successively from a loading position, to a splicing position, and finally to an expiring position. Also by moving the mechanism axially, the edges of the web, fed to the printing machine, are maintained in proper alignment. Before the leading end of a replacement roll can be spliced to a web running from an expiring roll, the replacement roll must be rotating at a peripheral speed approximately equal to the speed of the running web, and in order to accomplish this rotation, a plurality of running belts, moving at a speed approximately equal to the speed of the web, are operated in contact with the peripheral surface of the replacement roll. After the splice has been made, the same running belts are employed to control the feeding of the web. Heretofore, the reel has generally been rotated to bring the web roll into contact with belts mounted independently of the reel, and in order to provide continuous control for the web, auxiliary brakes have been used which act on the shaft or spindle of the web roll. In these machines, when the splice was about to be made, control of the web was transferred from the belts to the auxiliary brake.

This invention has for one of its objects the provision of a new and improved web-roll reel, having a single means that will speed up a replacement roll and control the feeding of the web throughout the whole operation.

Another object of the invention is to provide a new and improved web supplying mechanism capable of supporting a pair of web rolls, each of which is provided with its own speeding up and web controlling means.

Another object of the invention is to provide a new and improved web supplying mechanism having a single means that controls the web from the time that a new web roll begins to feed until the said roll has expired.

Still another object of the invention is to provide a new and improved tensioning mechanism

2

that will provide smooth, uninterrupted tensioning of the web.

With the foregoing and other objects in view, which will appear as the description proceeds, the invention resides in the combinations and arrangement of parts and in the details of construction hereinafter described.

A preferred embodiment of the invention is illustrated in the accompanying drawings wherein:

Figure 1 is an elevational side view of a web-roll supporting reel embodying features and principles of the invention;

Figure 2 is an enlarged sectional view of a portion of the mechanism shown in Figure 1;

Figure 3 is a view taken on the line 3—3 of Figure 2, and looking in the direction of the arrows, some parts being broken away to show details;

Figure 4 is a view taken on the line 4—4 of Figure 2, and looking in the direction of the arrows, some parts being broken away to show details;

Figure 5 is a view of a portion of the reel showing a valve and associated mechanism employed for controlling the speed up and tension belts;

Figure 5A shows the mechanism of Figure 5 with the valve in a different position;

Figures 6 to 9 are diagrammatic views of the reel in various positions through which it passes during its operation. Specifically, Figure 6 shows a roll in the feeding position, Figure 7 shows the same roll nearly depleted and a new roll in the loading position, Figure 8 shows the partly depleted roll being moved from the feeding position toward an expiring position, and Figure 9 shows the depleted roll in the expiring position and the new roll in the splicing position;

Figure 10 is a detailed cross-sectional view taken through the brush and knife carrier shown in Figure 3;

Figure 11 is a second cross-sectional view taken through the carrier shown in Figure 10;

Figure 12 is a view showing the valve and associated mechanism referred to in connection with Figure 5, as seen in the direction of the arrow 12 of that figure;

Figure 12A is a view of the valve shown in Figure 12, with certain portions broken away, the valve being in the position shown in Figure 5;

Figure 12B is a view of the valve similar to Figure 12A, but in the position shown in Figure 5A;

Figure 12C is a side view of the valve as viewed from the lowermost side of Figure 12A;

Figure 13 shows a modified form of the invention, in which certain parts are substituted for parts shown in Figure 2; and

Figure 14 is a view on the broken line 14—14 of Figure 13, as seen in the direction of the arrows.

Referring to the drawings, the invention is shown as applied to a reel 11 capable of supporting a pair of web rolls that may assume various positions in which they are hereinafter referred to as a new roll 10, a replacement roll 10', a feeding roll 15, and an expiring roll 12. The reel (Figure 1) includes a left frame 13 and a right frame 14, and the outer face of the left frame 13 is provided with a centrally located hub 16 from which a hollow cylindrical shaft 17 (Figure 2) extends and is journaled in a bearing 18 supported by a left column or post 19. The outer face of the right frame 14 is likewise provided with a hub 21 and a shaft 22 that is journaled in a bearing 23 supported by a right post 24. The two frames 13 and 14 are joined together by the rods 26 and 27, the rod 26 being held to frame 13 by a split lug 28 and tightening bolts 68, and to the frame 14 by a split lug 29 and tightening bolts 68. The rod 27 is likewise held to the frame 13 by a lug 31 and to the frame 14 by a lug 32. The extreme radially positioned portions of the frames 13 and 14 carry bearings 33 and 34, and 36 and 37 respectively. A web guiding roller 38 is rotatably supported between the bearings 33 and 37, and a similar web guiding roller 39 is supported between the bearings 34 and 36. The left frame 13 is provided with bearings 41 and 42 for rotatably supporting the left ends of the shafts 43 and 44 respectively, and the right ends of these shafts, in a similar manner are rotatably supported in bearings 46 and 47 carried by the right frame 14. The shafts 43 and 44 are driven, at a speed approximately proportional to the speed of the printing machine for the purpose of speeding up the rolls and tensioning the web, by means hereinafter described. A plurality of flanged pulleys 48 which drive the speed up and tensioning belts 49 are secured to the shaft 43 by bolts 51, and in like manner, the flanged pulleys 52 which drive belts 53 are secured to the shaft 44 by bolts 54. The belts 49 and 53 respectively, pass over movable pulleys 56 and 57, mounted in a manner hereinafter described. The mechanism thus far described forms a rotatable frame for carrying the roll supporting spiders and various apparatus utilized for handling and controlling the rolls during the cycle of operation shown in Figures 6 to 9.

A left spider 58 (Figures 1, 3 and 4) is slidably mounted on tie rod 26 by jaws 59 and 61 and secured where desired by clamp bolts 66. The opposite side of the spider 58 is likewise mounted and secured on the tie rod 27. A right spider 62 is similarly mounted on the same rods by jaws 63 and 64 and secured by clamp bolts 67. A gap 69 (Figure 4) is provided in each of the jaws 59, 61, 63 and 64, thus making it possible to move the spiders 58 and 62 past brackets 71 and 72, that are secured to the rods 26 and 27 respectively by screws 73, and serve to support the belt control mechanism described below.

Each spider (Figure 4) is diamond-shaped, having side members 74, 76, 77 and 78, and a diagonal member 79. The members 74 and 76 of spiders 58 and 62 respectively carry chucks 81 and 82 (Figure 1), of any known type, for rotat-

ably supporting the web roll 12, and the members 77 and 78 likewise carry chucks 83 and 84 (Figure 4) for supporting the web roll 10.

Each of the brackets 71 and 72 (Figure 1) carries a shaft 86 which pivotally supports a pair of axially bored bars forming air cylinders 87 and 88, each of which has a piston rod 92 (Figure 4), and forms means for controlling a belt. The outer end of each piston rod 92 carries a bracket 97, and adjacent pairs of these brackets and rods carry shafts 98 on which the movable belt pulleys 56 and 57 are rotatably supported. The closed ends of each pair of cylinders 87 and 88 carry a counter-weight 99 (Figures 1 and 4) for counterbalancing the pulleys.

Air or other fluid under suitable pressure is supplied to each of the air cylinders 87 and 88 through flexible hose connections 93 (Figures 5, 5A and 12), for forcing the piston rods 92 carrying the pulleys 56 and 57 outwardly to press the belts 49 and 53 against the web rolls 10 and 12 respectively. Hose connections 94 connect to the outer portions of the cylinders 87 and 88, and a two-way valve 96, to be hereinafter described, is provided whereby the air pressure against the pistons 91 may be made to withdraw the pulleys 56 and 57 and remove the belts from the web roll, to avoid driving the expired roll and unwinding paper after its web has been severed.

In a manner similar to that shown in U. S. Patent 2,357,259, the bearing 18 (Figures 1 and 2), which supports the hollow shaft 17, is in turn supported by a pair of rollers 101 and 102 that run on rails 103. In like manner, the right side of the reel 11 is supported by rollers 104 and rails 106. Also, in a manner similar to the method shown in the patent mentioned, a geared motor 107, having an output shaft 108 screwed into a threaded portion 109 of the column 19 is mounted on the bearing member 18, and provides means whereby the reel 11 and the web rolls 10 and 12 can be shifted longitudinally to adjust the alignment of the web W running to the machine. This adjustment moves the entire rotatable frame and spider assembly, including the speed up and tensioning belts, bodily.

The means for driving the shafts 43 and 44, and thus the belts 49 and 53, includes a shaft 111 (Figure 2) which is driven at a speed proportional to the speed of the printing machine by a suitable connection, not shown. The lower end of the shaft 111 is supported by bearings 112 and 113 and carries a bevel gear 114, meshing with a bevel gear 119 which has a hub 121 and is secured on a shaft 122 rotatably supported in a portion of a housing 123. The shaft 122 drives an adjustable V-belt pulley 124, having one face, 126, fixed to the shaft 122, and the other face 127 carried by hub 128 which is axially slidably on the shaft. The face 127 is held against axial motion on the shaft by a non-rotatable bearing plate 129 in which the hub 128 rotates and collar 131, screwed on the threaded end of hub 128 holds these parts together. Pin 132 fixed in and extending from the face 126 through holes in the face 127 causes the two faces to rotate in unison. Three shafts 133 are each provided with a right hand thread on one end and a left hand thread on the other end. One end of each shaft is screw threaded into the housing 123 and the other end is screw threaded into the plate 129. Each of the shafts 133 carries a sprocket 134 (Figure 3), and it will be seen that simultaneous rotation of these shafts will cause the plate, the collar 131, the hub 128, and the face 127 to move toward

or away from the face 126. The sprockets 134 are driven by a chain 136 which in turn is driven by a sprocket wheel 137, operated as hereinafter described. A second sprocket wheel 138 on the same shaft as the wheel 137, drives a chain 139 and sprockets 140 which adjust the diameter of a second adjustable pulley 141 having a face 142 secured to the shaft 143, and a face 144 mounted on a hub 145. A plate 147 like the plate 129, has a hub 148, and is moved by the shafts 149 in a manner similar to that previously described, except that when the diameter of the pulley 124 is increased, the diameter of the pulley 141 is decreased, and vice versa. By this means, the speed of pulley 141 relative to the shaft 111 may be varied as desired within the range of adjustment provided.

A bracket 151, secured to the post 19 by a plurality of bolts 152, supports the bottom of the housing 123 and also provides a bearing for the shaft 143. The inner end of this shaft carries a pinion 153, held in place by a key 154, and fitting within an internally toothed gear 156 secured on the end of a shaft 157 by a key 158. Hub 159 of the gear 156 and the shaft 157 are rotatable within a bore passing through the shaft 17. A double sprocket wheel 161 (Figures 2 and 4) secured to the shaft 157 by a key 162 is positioned within the frame 13 and drives a double chain 163, led over idler sprocket wheels 164 and 166. Chain 163 may be tightened by an eccentrically operated chain tightener 167. As seen in Figure 2, the sprockets 164 and 166 are secured to the end of the shafts 43 and 44 which carry the pulleys 48 and 52 and drive the belts 49 and 53.

The fixed frame posts 19 and 24, with other similar posts, not shown, support horizontally positioned structural members 169 and 171, and these members rotatably support guide rollers 172 and 173 (Figure 3), and a cross shaft 174 to which a pair of levers 176 is secured, for supporting a floating roller 177. An arm 178 also secured to the shaft 174 pivotally engages a link 179 and is thereby operably connected to a piston 181 movable in a cylinder 182, to which air pressure is supplied by a pipe 183. An arm 184 keyed to the shaft 174 is pivotally attached to one end of a rod 186 having a longitudinally acting spring 187 interposed therein. The other end of the rod 186 is pivotally connected to an arm 188 secured to the sprockets 137 and 138. Thus movement of the floating roller 177 acting through the chains 136 and 139 turns the sprocket wheels 134 and 140 and varies the diameter of the adjustable pulleys 124 and 141 so as to vary the belt speed and regulate the tension.

A combined knife and brush carrier 189 (Figures 3, 10 and 11), secured to the lower ends of a pair of pivotally supported arms 190, supports a brush 191, a knife 192, and an operating handle 193. While not in use, the arms 190 are biased to the position shown in Figure 3 by a spring 196, and a lever 194 that is part of the arm prohibits further movement by engaging a pin 197. In the construction shown, the reel and rolls carried thereby serve to clear their own paths of movement by forcing the carrier 189 back against spring 196. Where desired, however, any of the various known manual and automatic arrangements for positioning the carrier 189 according to the position of the reel and stage of the web feeding and splicing cycle, may be utilized.

The knife and brush mechanism as best seen in Figures 10 and 11, includes a tubular shaft

201 rotatably supported within a tube 202 and biased to rotate clockwise (as seen in Figure 10) by a coiled spring 203. This shaft carries a plurality of pins 204, the ends of which project through holes 206 provided in the tube 202, and these ends support bars 207 which carry a plurality of brushes 191, extending approximately the full length of the web rolls. A second shaft 208, also rotatably supported by the carrier 189, is biased to rotate counter-clockwise (as seen in Figure 10), by a coiled spring 209. This shaft carries the knife 192 which is held thereto by screws 211. The knife 192 and shaft 208 are held in a retracted position by a stop 212 carried by the shaft 208 and which engages the lower portion of a hook 213, pivotally supported on one end of a pivotally supported arm 214. A solenoid 216, supported from the carrier 189, has a plunger 217, the lower end of which is pivotally joined to one end of a link 218. The other end of the link is pivotally supported from the carrier 189 by a pin 219. An upper end of an arm 221, secured to the brush shaft 201, engages one end of the link 218, and when the solenoid 216 is not energized, holds the brush 191 in retracted position. While the arm 221 is held in the retracted position shown in Figure 10, a shoulder 222 on the arm engages the pivotally supported hook 213 and holds it in the position shown, retracted against the bias of a spring 223. Energization of the solenoid 216 raises the plunger 217, releases the arm 221 and allows the spring 203 to swing the brush against the web W. When the arm 221 has moved forward, the hook 213 is released and moves into engagement with a shoulder on the link 218. A second energization of the solenoid 216 then raises the hook 213, releases the stop 212, and allows the spring 219 to project the knife into position to sever the web from the expired roll. The mechanism thus described is reset by the handle 193 that is pivotally supported on lugs 224 and a pin 226. Moving the handle 193 to the left, as shown in Figure 11, moves a pin 227 to the right. This motion engages the upper end of a pivotally supported lever 228, the lower end of which engages a lever 229 secured to the end of the shaft 201, and rotates the shaft 201 counter-clockwise against the biasing spring 203. The lever 229 abuts against a lever 231 secured to the end of the knife shaft 208 by a clamp 210, and movement of this lever causes the shaft to rotate clockwise against the bias of the spring 209. Pulling the handle 193 farther in the same direction moves the arms 190 to the raised position hereinbefore mentioned.

The means for leading compressed air to the mechanism for controlling the belts and disclosed in Figures 5, 5A and 12 includes a pipe 232 shown in Figure 1, provided with a rotary coupling 233 and extending through the shaft 22 to the frame member 14, where it divides, one branch 232' (Figure 5) extending to the tie rod 27, along which it is carried in a groove as indicated in Figure 12, and the other branch (not shown) similarly extending to the tie rod 27.

While an air system, providing only for application of pressure to force the belts in the engaging direction, may be utilized, it is preferred to provide also for retraction of the belts. Figures 5, 5A and 12 show a preferred valve mechanism whereby the air pressure in the cylinders 87 and 88 may be reversed to lift the belt 53 engaging a roll in the expiring position, to the position shown in Figure 6 when a web splice

is made. A two-way valve 96 is mounted on the end of each of the tie rods 26 and 27 and outside the frame 13. Each valve 96 is pivotally supported on the end of its tie rod by a screw 241, and is normally biased to rotate in a clockwise direction by a spring 240 within the valve, but may be turned counter-clockwise to the limit of its motion and held in that position by a latch 242 which engages a shoulder 243 provided on the external surface of the valve 96. Each latch 242 is secured to a pin 244, rotatably mounted on the frame 13, and which carries a trip lever 247. The valves 96 cooperate with ports in the tie rods, each valve having a supply port 234 connected with the pipe 232', an outlet port 237 connected with a pipe 259, and another outlet port 238 connected with a pipe 258. An elongated slot 236 is formed in the face of the valve 96 and can be positioned to connect the supply port 234 with either of the outlet ports 237 or 238, and vents 237a and 238a are provided in the valve, and so positioned that the vent 238a will be aligned with the outlet port 238, when the supply port 234 is connected with the outlet port 237, and the vent 237a will be aligned with the outlet port 237 when the supply port 234 is connected with the outlet port 238.

When the reel is stopped in the position shown in Figure 9, and the valve 96 is being held by the latch 242, the trip lever 247 (Figure 12), will be in position to be engaged by a roller 248 supported on a lever 249 secured to one end of a shaft 251 which is carried in brackets 252 secured to the post 19. A solenoid 253 fixed on the post 19, has its plunger 254 connected to a bifurcated lever 256, arranged to turn the shaft 251 when the solenoid is energized.

The solenoid 253 is energized by operation of a switch 255 mounted on the carrier 189 (Figure 11) and is operated by rotation of the clamp 210 when the web severing mechanism operates. When the solenoid 253 is energized, the roller 248 engages the lever 247 and trips the latch 242, which allows the valve member 239 to turn closing the passage to the port 237 and opening the passage to the port 238. The valve is manually reset when desired by means of a handle 257.

The pipes 258 and 259, like the pipe 232', are carried in grooves in each of the tie rods 26 and 27, and these pipes are connected to the outlet ports 238 (Figure 5A), and 237 (Figure 5), respectively. Flexible hose connections 94 are connected to each of the pipes 259 (communicating with the ports 237), and lead to the inner ends of the cylinders 87 and 88, at points behind their piston faces 261. Also, hose connections 93 are connected to each of the pipes 258 (communicating with the ports 238), and lead to the outer ends of the cylinders 87 and 88, at points in front of the piston faces 262. Thus, when the valve 96 is positioned as shown in Figures 5 and 12A, the air pressure will act to force the piston rods 92 to their extended positions, whereas, when the valve 96 is positioned as shown in Figures 5A and 12B, the air pressure will act to force the piston rods 92 to their retracted positions, and the counterweights 99 will have moved the pulleys 57 and the belts 53, as shown in Figure 6, to a position where they will not interfere with the installation of a new roll 10.

The mechanism shown in Figures 13 and 14 is employed in connection with a somewhat modified form of the invention wherein the belts controlling the expiring roll are stopped when a web splice is made, instead of being automatically

lifted as shown in Figure 6. This is accomplished by disconnecting the shaft through which the belts on the expiring roll are driven, from its driving sprocket, and applying a brake by means of the solenoid 253. The mechanism shown in Figures 13 and 14 is mounted mainly within the frame 13, and is operated by the solenoid 253 mounted on the post 19. It includes a bracket 271 secured to the frame 13 by screws 272. This bracket carries a ball bearing 273, which rotatably supports one end of a shaft 44', corresponding to the shaft 44 hereinbefore mentioned, and the bracket has a tapered bore 274, the purpose of which will appear hereinafter. A clutch member 276, keyed to rotate with and mounted to slide axially along a reduced portion 277 of the shaft 44' includes a sleeve 278, the left end (Figure 14) of which has a clutch wheel 279 with a frustro-conical face 281 formed on its periphery. A brake wheel 282 with a frustro-conical face 283 is carried on the right end of the sleeve 278 and is secured thereto by screws 284. Bearings 286 supported on the left end of the shaft 44' rotatably support a sprocket wheel 166', which corresponds with the wheel 166 shown in Figure 2. A tapered bore 287 in the wheel 166' engages the clutch face 281 and drives the shaft 44' when the clutch member is positioned toward the left as shown in Figure 13. When the clutch member 276 is moved toward the right (Figure 13), the face 283 engages the bore 274 and thereby applies a brake action on the shaft 44'. Means for moving the sleeve 276 axially on the shaft, includes ball bearings 288, the inner races of which are secured to the sleeve at a point between the clutch wheels 279 and 282. The outer races of the ball bearings carry a ring 290 having a pair of pins 289 (Figure 14) that are engaged by the ends of a pair of arms 291 and 292, formed integral with a sleeve 293 secured to a shaft 294. The shaft 294 is journaled in the bracket 271 and has an operating handle 296 secured to one of its ends. A spring 297, carried in a bore 298 and coiled around the shaft 294 biases the sleeve 293 to cause engagement of the face 283 with the bore 274 and thereby apply a braking action to the shaft 44'. A lever 299 secured to one end of the shaft 294 may be engaged by a hook 301 formed as one lever of a bell-crank which is pivotally supported from the frame 13 by a bolt 302 and a shaft spring 303 biases the bell-crank to the position shown in Figure 14.

A second lever 304 of the bell-crank is provided with a ledge 304a that is engaged by the roller 248, in the same manner that the roller 248 engages the lever 247 shown in Figure 12. It will be understood that operation of the solenoid 253, which results in movement of the roller 248 in Figure 12 will similarly result in a corresponding movement of the lever 304 of Figure 14 when the solenoid 253 is energized. In Figure 12, energizing the solenoid trips the latch 242, releasing the valve and throwing off the belts, whereas in the device of Figures 13 and 14, operation of the solenoid releases the hook 301, which in turn releases the lever 299. This allows the spring 297 to turn the shaft 294, causing the arms 291 and 292 to disconnect the sprocket 166' and to apply a brake on the shaft 44' by engaging the face 283 with the bore 274, thus stopping the belts 53 and the roll 12. It will be understood that a sprocket like the sprocket 166' with the same cooperating mechanism is substituted for the sprocket 164 and its cooperating mechanism when using the form 75 of the invention shown in Figures 13 and 14.

Operation of the mechanism will best be understood by a reference to Figures 6 to 9. During normal feeding conditions, with the roll 15 in feeding position as in Figure 6, the web W will be led over the roller 172, over the floating roller 177 and the roller 173 (Figure 3), and thence to the printing machine (not shown). Tension of the web W feeding from the roll 15 will be controlled by the belts 49, and the speed of the belts will depend upon the speed of the machine and the effective diameter of the pulleys 124 and 141. In the loading position, Figure 6 or 7, the exhausted stub 12 will be removed and replaced by a fresh roll 10, at a convenient time.

If the tension on the web increases or decreases, the floating roller 177 will rise or fall against the stabilizing effect of the piston 181 (Figure 3). This will rotate the sprockets 137, 138, 134 and 140 (Figure 2) and adjust the diameter of the pulleys 124 and 141 to slightly increase or decrease the speed of the belts, as may be required to maintain a constant tension on the web. As the diameter of the web roll 15 (Figure 6) decreases, the air pressure against the piston faces 261 will cause the driving belts 49 and pulleys 56 (Figure 7) to follow the retreating surface of the roll. As the roll 15 nears exhaustion, the reel 11 is rotated counter-clockwise by means of a motor 308 (Figure 1), geared to a pinion 309 and a gear 300 in a well known manner, and moves the rolls 10 and 15 through the intermediate positions shown in Figure 8 to the positions shown in Figure 9, where the reel will be stopped by means of a suitable limit switch or photo-cell device (not shown), which acts to deenergize the motor in accordance with general practice. Figure 9 shows the roll 15 in the expiring position and the roll 10 in the splicing position.

With the web rolls thus disposed, the belts 53, being held in contact with the roll 10, will rotate it at a peripheral speed substantially equal to that of the web W being drawn from the expiring roll 12. As shown in Figure 9, the web passes around the roller 38 and is carried past the knife and brush carrier 189 and the replacement roll 10, and is thence carried over rollers 172, 177 and 173 to the printing machine. When it is desired to transfer the web feed to the replacement roll 10, the brush 191 is operated to press the web W against the surface of the replacement roll 10, and the web end of the roll 10 having previously been prepared with adhesive in a well known manner, it adheres to the running web W and is carried into the printing machine. The splice having thus been effected, and the machine then being supplied with a web from the roll 10, the web from the roll 12 is immediately severed by the knife 192. Energization of the solenoid 216 at the proper time, which is required in order to release the brush 191 and effect the splice, may be accomplished by utilization of a known photo-cell device operated by the passing of the adhesive on the roll surface or by passing of any other suitable mark placed in proper relation to the end of the web on the replacement roll, or alternatively a mechanically operated timing device of the order shown in Patent No. 2,140,528 may be employed.

When using the mechanism as illustrated in Figures 5, 5A and 12, the belts are automatically moved away from the roll when the web from the spent roll is severed, and when the form depicted in Figures 13 and 14 is used, the spent roll is automatically stopped when the web is severed.

It will be observed that the reel may be ar-

ranged with both the brake device of Figure 13, and also the hand operated valve mechanism of Figure 12, by omitting the trip lever 247 and utilizing the valve 96 as a means for throwing the belts out of contact with the rolls when they are being loaded into the reel or prepared for splicing.

It will be seen that the belts 49 and 53 maintain contact with the surface of the roll not only during the unwinding of the major portion of the roll, but also during the time it is being brought up to web speed, through the operation of splicing its web end to the then running web, through the period while the roll is being moved from the feeding to the expiring position, and while its web is spliced to the web end of the next roll to be used. Thus the same tension device controls the roll throughout all operations on it in the machine. This provides a continuous web tension control mechanism in which there is no disturbance of the web tension when changing the position of a running roll by rotation of the reel.

It will be understood that the invention may be embodied in other specific forms without departing from the spirit or essential attributes thereof, and it is, therefore, desired that the present embodiment be considered in all respects as illustrative and not restrictive, reference being made to the claims rather than to the foregoing description for an indication of the scope of the invention.

What is claimed is:

1. In a web supply device, a rotatable reel having means for rotatably carrying a plurality of web rolls for successively delivering a web therefrom, belt devices mounted upon said reel for movement therewith, means for positioning the belt devices for peripheral driving engagement with web rolls carried by the rotatable reel, means for driving the said belt devices from a machine being supplied with the web to accelerate a web roll prior to a splicing operation and to tension the same while supplying the web, and means for interrupting the drive of a web roll by a belt device upon severing of the web thereof following a splicing operation.

2. In a web supply device, a rotatable reel having means for rotatably carrying a plurality of web rolls for successively delivering a web therefrom, belt devices mounted upon said reel for movement therewith and positioned for peripheral driving engagement with web rolls carried thereon, adjustable speed belt driving means mounted on said reel for rotation therewith, and means for connecting said belt driving means to a machine drive external of the said reel.

3. In a web supply device, a reel having means for rotatably carrying a plurality of web rolls for successively delivering a web therefrom, shaft means for rotatably supporting said reel, belt devices mounted upon said reel for movement therewith and positioned for peripheral driving engagement with web rolls carried thereon, belt driving means mounted on said reel for rotation therewith and having an intermediate drive member coaxial with said shaft means and adjustable speed means responsive to tension of the web for driving said intermediate drive member from a machine drive external of the said reel.

4. In a web supply device, a rotatable reel having means for rotatably carrying a plurality of web rolls for successively delivering a web therefrom, belt devices mounted upon said reel for movement therewith and positioned for periph-

eral driving engagement with web rolls carried thereon, means for driving the said belt devices from a machine being supplied with the web to accelerate a web roll prior to a splicing operation and to tension the same while supplying the web, and means governed by the angular position of the said reel for unclutching and braking a belt device controlling an expiring roll upon splicing a web controlled thereby to a new web roll.

5. In a web supply device, a rotatable reel having means for rotatably carrying a plurality of web rolls for successively delivering a web therefrom, belt devices mounted upon said reel for movement therewith and positioned for peripheral driving engagement with web rolls carried thereon, means for driving the said belt devices from a machine being supplied with the web to accelerate the web roll prior to a splicing operation and to tension the same while supplying the web, and means governed by the angular position of the said reel for moving a said belt device controlling an expiring roll out of driving engagement with a web roll upon splicing a web being supplied therefrom to a new web roll.

6. In a web supply device, a fixed frame, a rotatable reel frame comprising end members and longitudinal tie rods connecting the said end members and spaced from the rotatable reel frame axis, pivotal supports associated with the said end members for mounting the rotatable reel frame on the fixed frame, an axially adjustable spider mounted on the said rotatable reel frame for rotatably carrying a plurality of web rolls for successively delivering a web therefrom, and driven belt devices for peripherally engaging web rolls carried by said spider along arcs thereof adjacent the reel frame axis and pivotally carried by said reel frame for movement toward and away from the axes of the said web rolls.

7. In a web supply device, a fixed frame, a rotatable reel frame comprising end members and longitudinal tie rods connecting the said end members and spaced from the rotatable reel frame axis, pivotal supports associated with the said end members for mounting the rotatable reel frame on the fixed frame, an axially adjustable spider mounted on the said rotatable reel frame for rotatably carrying a plurality of web rolls for successively delivering a web therefrom, driven belt devices for peripherally engaging web rolls

carried by said spider along arcs thereof adjacent the reel frame axis, and pivotally carried by said reel frame for movement toward and away from the axes of the said web rolls, and web guiding rollers carried by the said rotatable reel frame end members.

8. A web supply device for a printing machine, including a rotatable reel adapted to support a plurality of web rolls and web guiding means including a floating roller running in a loop in the web, in combination with a plurality of endless belts each carried on pulleys, pulley supports rotatable with the reel, first means to press the belts against the web rolls, second means connected to a rotating member of the machine to drive one of the pulleys carrying each belt, a variable speed device associated with the said second means, and third means operated in response to bodily movement of the floating roller to operate the variable speed device and thereby regulate the tension on a web running to the machine.

9. A web supplying device for a printing machine, including a rotatable reel adapted to support a plurality of web rolls, and web guiding means including a floating roller running in a loop in the web; in combination with a plurality of endless belts each carried on pulleys supported by and rotatable with the reel, means connected to a rotatable member of the machine to drive certain of the pulleys carrying the belts, and means responsive to bodily movement of the floating roller for controlling the action of each belt on a web roll, and thereby maintaining a desired tension on a web running to the machine.
